PRESSING MACHINE.

Application filed December 28, 1923. Serial No. 683,151.

This invention relates to pressing machines as garment and laundry pressing machines, such as are used in clothing factories, tailor shops, knitting mills, laundries, etc., and it especially has for its object a particularly simple and efficient and durable and also pedalless mechanism by which the power, if applied when the press is open, is ineffective on the movable pressing element 10 or head, and by which the closing of the press or the movement of the movable pressing element or head toward closed position a predetermined distance by hand is ineffective on the power mechanism, in other words 15 the invention has for its object an arrangement of parts of a motion transmission mechanism whereby if the power mechanism is actuated when the press is open, the motion thereof cannot be effectively applied 20 or transmitted to the pressing element or head or whereby no motion can be effectively transmitted unless such head has been preliminarily brought down toward the work by the operator or close to the work to a 25 "safety first" position, before the power is connected to the former mechanism. By safety first position is meant a position in which the operator cannot have his hands between the pressing elements. 30 The invention consists in the novel features and in the combinations and constructions hereinafter set forth and claimed.

In describing this invention, reference is had to the accompanying drawings in which 35 like characters designate corresponding parts in all the views.

Figure 1 is a side elevation of a machine embodying my invention, parts being omitted and the press being shown as open.

40 Figure 2 is a view similar to Fig. 1, the press being shown as closed when the power is applied.

Figure 3 is a fragmentary front elevation, parts being omitted.

45 Figure 4 is an enlarged detail view showing the mechanism for locking the clutch against operation when the toggle mechanism is near its dead center line.

Figure 5 is an enlarged fragmentary rear 50 elevation of the toggle links.

Figure 6 is a detail sectional view of the clutch for connecting and disconnecting the intermittently actuated cam to the motor driven shaft.

Figures 7 and 8 are fragmentary views of 55 modified forms of the toggle mechanism.

This pressing machine comprises, generally, coacting pressing elements, one movable toward and from the other, a carrier supporting the movable element, a power 60 member, motion transmitting connections between said member and the carrier, said connections including parts normally out of position to effectively transmit the motion of the power member to the carrier when 65 the press is open and movable into position to effectively transmit the motion of the power member when the movable pressing element has been moved by hand a predetermined distance toward closed position, manual means as a handle on the carrier or the 70 movable element to so move the movable element into preliminary closed position and means including a second handle for controlling the actuation of the power member. 75 The power member is intermittently actuated by means as an electric motor and the second handle controls the intermittent actuation of the power member.

1 and 2 designate the pressing elements 80 which are here shown as a so-called lower buck and an upper press head movable toward and from the buck, the buck 1 being usually stationary and carried by the bracket or so-called goose neck 3 which in turn is 85 mounted upon a table 4 suitably supported by a frame 5.

The upper press head 2 is here shown as supported by a movable carrier as a lever or yoke 6 pivoted between its ends at 7 to a 90 standard 8, extending upwardly from the frame, the press head 2 being carried by the forward arm of said lever in any suitable manner, such forward arm being provided with a handle 9 at its front end. The rear 95 arm of the lever 6 is usually provided with a suitable counterweight 10 and also usually has connected thereto a spring 11 acting in conjunction with the counterweight. The counterweight 10 and spring 11 constitute 100 means tending to open the press when no force is applied or active, tending to close the press or hold it closed. The handle 9 is a manual means for preliminarily closing the press against the counterweight 10 and 105 spring 11 or other means tending to open the press, and for holding it closed until the power member is actuated.

12 designates the power member which is here shown as a lever pivoted at 13 between its ends to the lower part of the frame near the floor, this power lever extending forwardly and rearwardly of the machine. The power lever is actuated by an intermittently movable motor driven actuator as will be hereinafter described.

The connections between the power lever 12 and the carrier lever 6, are constructed to be ineffective to transmit the motion of the power lever 12, if actuated when the press head is up and also ineffective to transmit the motion of the carrier 6 to the lever 12 when the press is being closed or the press head 2 is being moved a predetermined distance toward closed position by the operator. These connections comprise links 14 and 15 pivoted respectively to the rear arm of the carrier 6 and to the rear arm of the power lever 12 and capable of moving freely on such pivots relatively to the carrier 6 and the power lever 12, such levers being connected together by a lost motion connection which is not taken up until the press head 2 has been moved a predetermined distance by hand or to nearly closed position, and the toggle links 14 and 15 moved into or near or beyond the dead center line of the toggle and to such position that the movement of the power lever 12 is effective on the carrier 6. These connections further comprise means for preventing the toggle links from unfolding when the lever 12 is actuated and after the links 14 and 15 have been moved into or nearly into or toward the dead center line of the toggle links 14 and 15 by such closing movement of the head 2.

The link 14 as here shown, is pivoted at 16 to the rear arm of the carrier lever 6 and the link 15 is pivoted at 17 to the rear arm of the power lever 12. The link 15 extends rearwardly from the power lever 12 when the press is open, and is movable into a position at or nearly at a right angle to the lever 12 when the head 2 has been pulled down by hand toward closed position a predetermined distance. The lost motion connection between the links 14 and 15 is of such a nature as to merely move the link 15 from its normal nearly horizontal position, Fig. 1, into a position approaching a right angle to the lever 12 when the head 2 is pulled down by the operator, so that the links 14 and 15 idle during the closing of the press head 2 by the operator, or when the power lever 12 is actuated before the head is pulled down.

This lost motion connection is preferably a pin 18 provided on the lower end of the link 14 and a lengthwise slot 19, in which the pin works in the link 15, the pin moving downwardly in the slot and lifting the link into vertical position during downward movement of the press head by hand, so that,

when the press head has been closed a predetermined distance by hand the pin is at the lower end of the slot and hence, when the power is applied to the lever 12, the link 15 or bottom of the slot 19 thrusts upwardly 70 against the pin 18 and thrusts the link 14 endwise upwardly and forwardly and rocks the carrier lever 6 on its pivot to apply comparatively heavy pressure to the head 2. The bottom end wall of the slot 19 and the pin 18 constitute shoulders normally out of abutting relation and movable into abutting relation by the preliminary closing of the press head 2 by hand.

As the lever 15 is pivoted loosely at both 80 of its ends and also as the lever 14 is pivoted loosely at both of its ends, means is provided for preventing the unfolding of the links 14 and 15 at the pin and slot joint 18, 19 when the power is applied to the lever 12 85 after the press head 2 is closed or brought down by hand a predetermined distance. This means, as here shown, consists of a third link 20 pivoted idly or loosely at the lever 14 and to the frame and being arranged out of parallelism with both links 14 and 15 when they are in any position and particularly when they are in straight position or nearly straight position.

The link 20, as here shown, is pivoted at 21 to the link 14 above the pin 18 and at its other end to the frame preferably coaxially with the power lever 12 or on the same pivot or shaft 13 that the power lever is mounted on, although such link 20 may be differently arranged to guide the links 14, 15 during the application of power to the power lever 12. The link 20 being mounted on a different center from the link 15 which causes its pivotal point 21 to move in an arc having a different curvature from the arc of movement of the pin 18. Obviously during the movement of the press head 2 downwardly by hand from the position shown in Fig. 1, toward that shown in Fig. 2, the links 14, 15 and 20 will move nearly into their position occupied in Fig. 2, and during such movement the pivot points 18 and 21 will move in the arc $x-x$ and $y-y$ respectively. As the links approach their position shown in Fig. 2, the arc $y-y$ having a greater forward and upward curvature than the arc $x-x$, obviously the pressure is applied through the act of the toggle consisting of the links 14 and 20 and the link 15 110 tends to move the links 14 and 20 toward the dead center line passing through the centers 13. As seen in Fig. 5, the link 20 is 115 double and embraces the links 14, 15.

It is the movement of the links 14, 20 toward their dead center line or the movement of the pivot 21 in the arc $y-y$ that applies the pressure to the head 2 or carrier 6, and the toggle consisting of the links 14, 20 is actuated by the power lever 12 through the 120 125 130

additional or second link 15 which is a thrust link pivotally or foldably connected to the power lever 12, and to one of the toggle links 14, 20, it being connected to one of the parts to which it is connected by a lost motion, or pin and slot connection arranged to be taken up by the manual movement of the head 2 and the carrier 6 a predetermined distance toward closed position and the consequent movement of the links 14, 20.

If the power is applied to the lever 12 before the head 2 is brought down to a predetermined position, these connections consisting of the parts 14, 15 and 20, will at the most again move the head upwardly or open the press instead of closing it. If the power is applied to the lever 12, while the head is open practically no motion will be transferred to the head or at the most a slight oscillating movement. If desired, in order to prevent the head from being actuated at all from the power lever 12 until the head has been brought down to a predetermined position, the rear side of the slot 19 may be omitted or the slot widened, as shown, in Fig. 7, or the lever 15 may normally stand in starting position, near the effective position thereof or inclined slightly out of vertical, as shown in Fig. 8, and be picked up by the link 14 when the head 2 has been pulled by hand a predetermined distance and moved by the link 14.

The link 14 is adjustable endwise to permit the head 2 to do different thicknesses or work, and as here illustrated, includes a turn buckle section consisting of a right and left threaded rod 14^a and an operating hand wheel 14^b keyed thereto. The wheel 14^b is slidably keyed at 14^d to the rod and has a socket 14^e for receiving an angular head 14^c. In operation to lengthen or shorten the link 14, the wheel 14^b is shifted upwardly to disengage the socket from the head 14^c, and the wheel turned in one direction or the other, the wheel is then again shifted downwardly so that the socket receives the head, and hence holds the wheel and the rod from turning.

The power lever 12 is preferably actuated in one direction by motor power, the application of which is controlled by an additional handle, which must be operated while the operator has hold of the handle 9, and as here shown, it is actuated from a constantly running electric motor by an intermittently movable cam, which is always engaged with the lever. The power lever is actuated in the other direction by a spring 12^a which carries the lever 12 to follow the cam.

22 designates the cam which is carried by a shaft 23, the cam being here shown as an eccentrically mounted pin having a roller 24 thereon, which engages a wearing face 25 on the front end of the lever 12. The lever

is held against the roller to follow the same by the spring 12^a. This shaft 23 is journaled in suitable bearings 26 carried by a suitable casing 27 supported by a bracket 28 carried by a frame member 29, and is actuated intermittently one-half revolution by a motor supported on the frame and having its shaft 31 or extension thereof provided with a worm 32 meshing with a worm gear 33 mounted to rotate about the shaft 23 and to be connected thereto and disconnected therefrom periodically by a half revolution or periodic clutch designated generally 34. This clutch is operated by a suitable hand lever 34^a which is operated by the operator when the head 2 is brought down. If this lever is operated to throw the clutch before the head is brought down, the cam makes a half revolution and actuates the lever 12 but the movement of the lever 12 is ineffective on the carrier lever 6 on account of the operation of the toggle links 14, 15 and 20, as before explained. However, the machine is now out of synchronism or sequence, as the power lever 12 is depressed, and the press is open while in the proper sequence the power depressed when the press is closed. In order to restore the synchronism or sequence it is necessary to again operate the lever 34^a to connect the clutch 34 to the worm gear 33, so that the clutch in making a half revolution will again rotate the cam 22 a half revolution.

The clutch 34 may be of any suitable form, size and construction and the construction thereof per-se forms no part of this invention. It is sufficient to bear in mind that the clutch is operated by the operator to connect the constantly running motor to the cam shaft 23 and is automatically disconnected when the cam has made a half revolution.

The clutch here illustrated comprises an axially shiftable disk or carrier 35 having a hub 36 mounted to rotate about the shaft 23, a floating thrust ring 37 opposed to the disk 35, a guide 38 between the thrust ring 37 and the worm gear 33, a plurality of pins 40 slidably in aligned openings in the guide disk 38, thrust ring 37, and carrier disk 35, these pins having shoulders 41 against which the thrust ring 37 thrusts, one or more springs, as 42, tending to separate the thrust ring 37 and the carrier disk 35, a main spring 43 tending to shift the ring 35 in one direction, as to the right, to disconnect the clutch, manual means for shifting the ring 35 to the left against the spring 43, and means for holding the carrier ring 35 in its manually shifted position during the half revolution of the clutch. The gear wheel 33 is provided with a circular series of holes 45 for receiving the pins 40 and thus locking the gear wheel 33 to the

guide ring 38 which guide ring is keyed to the shaft 23. As here illustrated, the gear wheel 33 is mounted on a hub 46 on one side of the guide ring 38 and the guide ring has 5 another hub 47 on the other side thereof which is keyed to the shaft 23 as by a transverse key 48.

The means for shifting the clutch, as here shown, comprises a shifter or rock arm 49 mounted on a rock shaft 50 journalled in 10 the casing 51 of the clutch, this rock shaft being operated to the left by the lever 34^a and connections controlled by said lever. The arm 49 thrusts against one end of the hub 15 36 of the carrier ring 35 and when rocked in one direction serves to shift the carrier to the left; and the carrier serves to shift the thrust ring 37 through the springs 42 to the left and thus move the pins 40 in the openings 45 into the gear wheel 33. In the event 20 the pins 40 do not register with the holes 45, the springs 42 compress or yield and then, when the pins are registered with the holes 45, react and thrust the pins 40 into the holes 25 45. Thus the lever 34^a can be thrown to its full extent by the operator regardless of whether or not the pins 40 are alined with the holes 45.

The means for holding the ring in its 30 shifted position until the clutch has made a half revolution comprises a circular track 52 supported by the cover or the case 51 concentric with the shaft, 23 and having notches 56 preferably diametrically opposite each 35 other for receiving the followers or rollers 57 on the carrier 35. Upon operating the shaft 50, the carrier 35 is thrust to the left carrying the rollers 57 out of the notches 56, so that the clutch now being engaged 40 will start on its half revolution and the rollers will ride on the face of the ring 52 until the rollers again come into alinement with the notches 56 after the clutch has made a half revolution. When the clutch 45 has completed its half revolution, that is, when the rollers have again come into alinement with the notches 56, the spring 43 thrusts the carrier 35 to the right to carry the rollers 57 into the notches 56.

50 The connections between the lever 34^a and the rock shaft 50 for shifting the clutch 34, comprises an upwardly extending arm 58 on the rock shaft 50, a rock shaft 59 supported in a suitable bearing in the upper end of the 55 frame 5 near the table 4, a rock arm 60 on such shaft 59, a pawl 61 pivoted at 62 to the rock arm 60 and having one end arranged to engage the lever 58, the lever 34^a being mounted upon the rock shaft 59, and a 60 spring 63 tending to rock the shaft 59 in the direction opposite to that by which it is rocked by the lever 34^a. Upon depression of the lever 34^a the rock shaft 59 is rocked in one direction as to the right moving the 65 rock arm 60 thereon to the right, causing the

end of the pawl 61 to engage the upper end of the arm 58 and move such arm to the right and thus rock the shaft 50 to shift the shifter arm 49 to the left and hence shift the carrier ring 35 of the clutch 34 to the left to engage the clutch or shift it to "in" position. The clutch is held in "in" position by the track 52 as heretofore described and when the lever 34^a is released the spring 63 returns it and the shaft 59 to its normal 70 position. As the arm 60 swings in an arc upwardly away from the arm 58, the pawl in passing upwardly passes out of engagement with the arm 58, this occurring after the clutch 34 has been thrown "in". During 75 retrograde movement of the shaft 59 and the lever 34^a, the pawl 61 slides over the upper end of the arm 58. Pivotal movement of the pawl 61 is prevented while the pawl is operating or thrusting against the arm 58, 80 by a shoulder 64 on the arm 60 which shoulder engages the tail of the pawl 61. The arm 58 is inclined to the left and the weight thereof moves it to its normal position as soon as it is free of the pawl 61. However, 85 the thrust of the hub 36 of the carrier ring 35 of the clutch 34 to the right by the main clutch spring 43 would also return this lever 90 58 to its normal position.

At an intermediate point between the positions occupied by the head 2 when it is open and the position occupied when pulled down by hand to a predetermined position, the toggle mechanism, is at such a point for convenience called a neutral point, that if the power 95 were applied from the lever 12 the head 2 and the lever 6 would be thrown upwardly with a more or less violent jar due to the toggle links 14, 15 and 20 unfolding backwardly, or the head might be thrown down by 100 power.

In other words there is an intermediate or neutral point which the head 2 and the lever 6 may occupy between open position and a predetermined closed position, where if the power were applied from the lever 12 105 the links 14, 15 and 20 would hesitate on account of the small leverage whether to unfold and open the press or to continue toward straight position and close the press. 110

In order to prevent the application of the power at such intermediate or neutral point, means is provided for preventing the operating of the lever 34^a until the press head 115 has been pulled down by hand beyond such intermediate or neutral point. Such means would be unnecessary after the operator learned to pull down the head to such predetermined point. Such means comprises a lock operable to lock the handle 34^a from 120 operation when the press head and parts moved thereby are in such intermediate or neutral point. The lock comprises a rack 65 on a sector or arm 66 mounted on the shaft 59 to rock therewith, and an endwise mov- 125 130

able rod or bolt 67 operated by the movement of the lever 6 or some part movable with such lever as the toggle link 14, the rod 67 having a tooth 68 arranged to be moved 5 into engagement with the rack 65 when the links 14 and 15 are at or near such intermediate or neutral point. As here shown, the rod 67 is carried in suitable guides 69, carried by the frame and is pressed rearwardly 10 so that its tooth 68 will engage the rack 65 by a spring 70 and is pressed out of engagement by a cam 71 on the link 14. This cam has high points 72 and 73, and intermediate low point 74 between the high points. The 15 high points 72 and 73 press the rod forward to hold the tooth 68 out of engagement with the rack 65 when the press head is open and during its movement toward such intermediate point, and after the press head has 20 passed such intermediate point; and the low point 74 of the cam permits the spring 70 to move the rod 67 endwise rearwardly and hence engage the tooth 68 with the rack 65 when the head is in the neighborhood of intermediate point. Thus when the head is 25 open, the lever 34 can be operated, and the cam 22 actuated to depress the lever 12, but the link 15 idles and very little or no movement will be transmitted to the press head. 30 And when the press head is pulled way down to a predetermined point and the lever 34^a is actuated, the motion of the lever 12 will be effectively transferred to the press head 2. But if the operator neglects to pull the 35 head down a predetermined distance, the operating lever 34^a is locked so that the clutch 34 can not be thrown to cause the cam 22 to actuate the lever 12, the lever 34^a locking when the head is pulled down to an intermediate position, and not to a predetermined or 40 fully closed position, by the fact that the lock rod 67 is opposite the low point 74 of the cam 71 and is moved by the spring 70 to the right, Fig. 4, carrying the shoulder or 45 tooth 68 into mesh with the rack or sector 66 on the shaft 59 which is actuated by the lever 34^a, and thus locks the shaft 59 from being rocked.

A suitable buffer is provided for limiting the opening movement of the head. 50 This buffer may be provided between the frame lever 6 and the main frame 5 near the pivot 7, of the lever 6, or to coact with any part movable with the lever 6. As here shown a buffer is provided on the intermediate part of the lever 20 and engages a stop surface on the rear arm of the power lever 12.

75 designates the buffer on the lever 20 and 76 a stop surface on the rear end of the lever 12, the buffer 75 coming in contact with the stop surface 76 when the press is open, as shown in Fig. 1. However in the 60 illustration of the toggle mechanism, shown 65 in Figs. 7, and 8, the buffer is preferably

located as at 77, between the forwardly extending arms 78 of the counterweight and the opposite surface of the standard 8.

In the operation of the machine, assuming that it is in the position shown in Fig. 1, 70 the operator places the garment or other article on the lower buck, takes hold of the handle and pulls downwardly thereon moving the head 2 toward the buck, so that, there is very little space between the head and the work on the lower back. Such movement carries the links 14, 15 and 20 from their inactive position shown in Fig. 1 to near but not quite their effective positions shown in Fig. 2. The operator then depresses the 80 lever 34^a throwing "in" the clutch 34 and thereby connecting the motor to the cam shaft 23, whereby the cam 22 makes a half revolution to the position shown in Fig. 2, thus depressing the lever 12 which in turn 85 moves the links 14, 15 and 20 into the position shown in Fig. 2, thus transmitting comparatively heavy pressure to the head 2. The cam 22 remains engaged with the lever 12 and holds the pressure as long as desired. 90 When the lever 34^a is again operated to throw in the clutch 34, the clutch 34 makes another half revolution from the position in Fig. 2, to that shown in Fig. 1, permitting the spring 12^a to pull the lever 12 upwardly and causing the lever to follow the cam 22, and also permitting the counter weight 10 and spring 11, to open the press. 95

As the lever 12 follows the cam 22 during the opening of the press, the opening of the 100 press is controlled by the cam so that the press opens evenly and without jar or shock.

The press is particularly advantageous in that it is pedalless and must be closed by one hand, to a "safety first" position before the 105 power controlled by the other hand, can be effectively applied thereto, and in that it operates evenly as the actuating cam is constantly engaged with the power lever and no lock and latch mechanisms are necessary 110 to hold it preliminarily in "safety first" position or in final pressing position.

What I claim is:

1. In a pressing machine, the combination of a supporting frame, cooperating pressing elements, one movable toward and from the other, and preliminarily movable by the operator toward the other, a carrier supported by the frame and carrying the movable pressing element, the other element being carried by the frame, a power member, connections between the power member and the carrier comprising links, one connected to the carrier and movable therewith during the preliminary movement of the carrier by the operator and the other link being connected to the power member to move therewith, said links being normally out of position to transmit motion one to the other, and means whereby movement of the link 125 130

connected to the carrier by the carrier when the carrier is moved manually to close the press brings said links into motion transmitting position and power means coacting 5 with the power member to actuate it.

2. In a pressing machine, the combination of a supporting frame, cooperating pressing elements, one being movable toward and from the other and preliminarily movable 10 by the operator toward the other, a carrier supported by the frame and carrying the movable pressing element, the other pressing element being mounted on the frame, a power member, connections between the power member and the carrier comprising links pivoted together one link being pivoted to the carrier and movable therewith during the preliminary operation thereof, and the other to the frame whereby both links shift 15 and change their position during the preliminary movement of the movable element by the operator toward closed position and a thrust member pivoted to the power member and arranged to act on one of the links, 20 and the link with which it cooperates having a shoulder and the thrust member also having a shoulder, the shoulder on the link being arranged to come into abutting relation with the shoulder on the thrust member 25 by the movement of the links caused by the preliminary movement of the movable element, and power means coacting with the power member.

3. In a pressing machine, the combination 35 of a supporting frame, cooperating pressing elements, one being movable toward and from the other and preliminarily movable by the operator toward the other, a carrier supported by the frame and carrying the movable pressing element, the other element being mounted on the frame, a power member, connections between the power member and the carrier comprising links pivoted respectively to the carrier and to the power 40 member and having shoulders normally spaced apart and arranged to come into abutting relation by the movement of the link pivoted to the carrier when the carrier is moved preliminarily to carry the movable element toward the other element, and a third link pivoted to the frame and to the link which is pivoted to the carrier.

4. In a pressing machine, the combination 55 of a supporting frame, a cooperating pressing elements, one of which is movable toward and from the other, and preliminarily movable by the operator toward the other, a movable carrier supported by the frame and carrying the movable element, the other element being mounted on the frame, a power member, a link pivoted to the carrier, a second link pivoted to the power member and connected to the first link by a lost motion connection and a third link pivoted to 60 the frame and to the first link and diverging

out of parallelism with the first and second links, the third link being of a different length from the second link and the pivots connecting the second link and the power member, and the third link to the frame being spaced apart. 70

5. In a pressing machine, the combination of a supporting frame, cooperating pressing elements, one movable toward and from the other and preliminarily movable by the operator toward the other, a carrier supported by the frame and carrying the movable pressing element, the other pressing element being mounted on the frame, a power member, a link pivoted to the carrier, a second link pivoted to the power member, the first and second links having abutting shoulders normally out of abutting relation and movable into abutting relation by the preliminary movement of the movable element toward the other element and a third link pivoted to the frame and to the first link and diverging out of line with the first and second links. 80

6. In a pressing machine, the combination 90 of a supporting frame, cooperating pressing elements, one being movable toward and from the other and preliminarily movable by the operator toward the other, a carrier supported by the frame and carrying the movable pressing element, the other pressing element being mounted on the frame, a power member, links pivoted together one being pivoted to the carrier and the other to the frame and a connection comprising 100 a thrust member between the power member and one of the links to move the links toward straightened position after the same have been initially brought toward nearly straightened position by the preliminary 105 movement effected by the operator, said thrust member and the link pivoted to the carrier having shoulders arranged to be brought into abutting position by the preliminary movement of the movable element 110 toward the other element.

7. In a pressing machine, the combination of a supporting frame, cooperating pressing elements, one movable toward and from the other and preliminarily movable by the operator toward the other, a carrier supported by the frame and carrying the movable pressing element, the carrier having a handle for moving the movable element preliminarily toward the other element, the other element being mounted on the frame, a power member, motion transmitting connections between said member and the carrier including parts normally out of effective motion transmitting position and means 120 to bring the parts into effective motion transmitting position by the preliminary closing movement of the press, means constantly tending to move the carrier and the movable element to open position, an intermittently 125

actuated cam coacting with the power member and constantly engaged therewith, and means including a second handle for controlling the actuation of the cam.

5. 8. In a pressing machine, the combination of a supporting frame, cooperating pressing elements, one being movable toward and from the other and preliminarily movable by the operator toward the other, a carrier supported by the frame and carrying the movable pressing element, the carrier being provided with a handle by which the movable element is preliminarily moved to and held in its preliminarily closed position, the other pressing element being mounted on the frame, a power lever, links pivoted together, one being pivoted to the carrier and the other to the frame, an additional link pivoted to the power lever and arranged to coact with one of the former links, said additional link extending in the same general direction as the link pivoted to the frame and being located out of parallelism therewith, the additional link and the link with which it coacts being provided with shoulders arranged to be brought into abutting relation upon movement of the movable pressing element toward the other element, whereby said links provided with the shoulders are connected by a lost motion connection arranged to be taken up by the preliminary movement of the movable pressing element toward closed position and the consequent movement of the carrier and the links, means constantly tending to actuate the carrier to move the movable element to open position and an intermittently actuated part coacting with said power lever to actuate it, and means comprising a second handle for controlling the actuation of said part.

9. In a pressing machine, the combination of a supporting frame, cooperating pressing elements, one being movable toward and from the other and preliminarily movable by the operator toward the other, a carrier supported by the frame and carrying the movable element, the other element being mounted on the frame, a power member, motion transmitting connections between said member and the carrier including motion transmitting parts normally out of operative position and means operative to move the parts into operative position by the preliminary movement of the movable pressing element toward the other element, motor mechanism for actuating the power member including a controlling element, said connections having a neutral point and means for preventing the actuation of the controlling element when said connections are in the neighborhood of the neutral point.

10. In a pressing machine, the combination of a supporting frame, cooperating pressing elements, one movable toward and from the other and preliminarily movable by the

operator toward the other, a carrier supported by the frame and supporting the movable element, the other element being mounted on the frame, a power member, a part connected to the power member and a part connected to and movable with the carrier, said parts having shoulders normally out of abutting relation and means to bring the parts into abutting relation by the preliminary movement of the carrier effected by moving the movable element toward the other element, manual mechanism for controlling the actuation of the power member including a controlling element and means for preventing actuation of the controlling element when said motion transmitting parts are in the neighborhood of a neutral position, said means comprising a rock shaft movable with the controlling element and having an arm thereon, a movable bolt for coacting with said arm and arranged in the path of the movable part connected to the carrier to be shifted thereby into engagement with the arm on said shaft when the parts are in an intermediate portion of their path of movement.

11. In a pressing machine, the combination of a supporting frame, cooperating pressing elements, one movable toward and from the other and preliminarily movable by the operator toward the other, a carrier supported by the frame and carrying the movable pressing element and having a handle for moving the movable element preliminarily toward the other element, the other element being mounted on the frame, a power member, connections between the power member and the carrier comprising motion transmitting parts normally out of operative engagement and means for moving the parts into operative engagement by the preliminary closing movement of the movable element, means constantly tending to actuate the carrier in a retrograde direction and move the movable element to its open position, power means coacting with the power member to actuate it including an intermittently movable actuator coacting with the power member, a motor, connections between the motor and the intermittently movable actuator and means having a second handle for controlling the operation of said connections.

12. In a pressing machine the combination of a supporting frame, cooperating pressing elements, one movable toward and from the other and preliminarily movable by the operator toward the other, a carrier supported by the frame for carrying the movable pressing element and having a handle by which it is preliminarily moved to carry the movable element toward the other element, the other element being mounted on the frame, means acting on the carrier to move it and the movable element out of

the position they are moved by the handle, a power member and connections between the power member and the carrier comprising normally separated, out of thrusting relation, motion transmitting parts movable into abutting engagement, power means co-acting with the power member to actuate it comprising an intermittently movable

actuator, and means including a second handle for controlling the actuation of the power means. 10

In testimony whereof, I have hereunto signed my name, at Syracuse, in the county of Onondaga, in the State of New York, this 18th day of December, 1923.

ALBERT B. CLISSON.
